FIG. 15

FIG. 1 is a perspective view of a water closet embodying my new design;

FIGS. 2, 3 and 4 are front, side and rear elevational views, respectively, thereof;

FIG. 5 is a bottom plan view thereof;

FIG. 6 is a perspective view of a modified form of the water closet shown in FIGS. 1-5;

FIGS. 7, 8 and 9 are front, side and rear elevational views, respectively, thereof;

FIG. 10 is a bottom plan view thereof;

FIG. 11 is a perspective view of another modified form of the water closet shown in FIGS. 1-5;

FIGS. 12, 13 and 14 are front, side and rear elevational views, respectively, thereof; and

FIG. 15 is a bottom plan view thereof.

The sides not shown are substantially the same in appearance as the respective sides shown.

The characteristic features of my design for the water closet disclosed reside in the configurations of the forward portions comprising the bowl and base thereof.

I claim:

The ornamental design for a water closet, as shown and described.
